UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

DESIGN FOR AN AUTOMOBILE BODY SIDE.

Application filed August 23, 1927. Serial No. 23,185. Term of patent 14 years.

To all whom it may concern:

Be it known that I, JOSEPH LEDWINKA, a citizen of the United States, residing at Philadelphia, in the county of Philadelphia, State of Pennsylvania, have invented a new, original, and ornamental Design for Automobile Body Side, of which the following is a specification, reference being had to the accompanying drawings, forming part thereof, wherein

Fig. 1 is a side elevational view of an automobile body embodying the design, the portion included in the design being shown in full lines.

Fig. 2 is a front elevational view thereof showing how the opposite sides of the body converge toward the front.

I claim:

The ornamental design for an automobile body side, as shown.

Signed at Philadelphia, in the county of Philadelphia, in the State of Pennsylvania, this 19 day of August, 1927.

In testimony whereof I hereunto affix my signature.

JOSEPH LEDWINKA.
